UNITED STATES PATENT OFFICE.

FREDERICK C. GRAF, OF BROOKLYN, AND MICHAEL J. ZWOSTA, OF NEW YORK, N. Y.

AUTOMATIC TRAIN CONTROL.

1,412,816.

Specification of Letters Patent. Patented Apr. 11, 1922.

Application filed July 19, 1920. Serial No. 397,191.

To all whom it may concern:

Be it known that we, FREDERICK C. GRAF and MICHAEL J. ZWOSTA, both citizens of the United States, and residents, respectively, of the city of New York, borough of Brooklyn, in the county of Kings and State of New York, and city of New York, borough of Queens, county of Queens, and State of New York, have invented a new and Improved 10 Automatic Train Control, of which the following is a full, clear, and exact description.

This invention relates to an automatic train control system which is operable in conjunction with the signal systems now in use or which may be independently operated by a separate system with equal efficiency.

Various signal systems have been employed satisfactorily where the rules governing their use have been strictly observed by the train operators, but numerous and frequent accidents have occurred by the failure of operators to observe the signals.

This invention therefore broadly contemplates the provision of an automatic train control system which entirely eliminates the failure on part of the human element and which seeks to conform strictly with the requirements defined by railroad experts as a prerequisite to the practicability of a device 30 of this character.

The control systems for this purpose which have been heretofore employed largely include trip devices on the train which are adapted to contact with ramps or other devices adjacent the track and it is one of the specific objects of this invention to eliminate the use of means of this character by resorting to means operating in conjunction with the air brake system which is controlled by 40 normally closed circuit adapted to be broken should the train attempt to enter an occupied block ahead.

A further object of the invention is to provide an apparatus which is so constructed 45 that it will perform its intended function if any essential part fails or is removed, or if a brake, cross, ground, short circuit or other failure of energy in the electric circuits occurs when in use.

50 A still further object of the invention is to provide an apparatus or system of the character described which will operate under all conditions of speed, weather, wear, oscillation and shock.

55 A still further object of the invention is to provide a fool-proof system and apparatus

which will defeat any attempt of an engineer anticipating a closed signal from passing the same, said apparatus being provided with means which functions to stop the train immediately upon manipulation of the apparatus with such an intent.

A still further object of the invention is to provide an apparatus which includes means which permits the train to pass a closed signal at a predetermined reduced rate of speed.

Another object of the invention is to provide a train control system which comprises means for automatically closing the throttle or electric switch as the case may be prior to the application of the brakes.

Another object of the invention is to provide an automatic drain for preventing accidental application of the brakes due to leakage of the air from the main reservoir pressure to the operating mechanism.

A still further object of the invention is to provide adjustable means whereby the apparatus may be set for either a "service" or "emergency" stop.

With the above recited and other objects in view, some of which will be apparent hereafter, reference is made to the following detailed description, claims and accompanying drawings forming a part of this application, and in which;

Figure 1 is a diagrammatic illustration of the application of the apparatus to a locomotive.

Figure 2 is an enlarged sectional view of a part of the system.

Figure 3 is a detail sectional view of the electrically operated latch taken approximately on the line 3—3 of Figure 2.

Figure 4 is a diagrammatic detail view of a speedometer controlled circuit closer constituting one of the features of the invention.

Figure 5 is a detailed sectional view of the reset and drain valve.

Figure 6 is a diagrammatic plan view of the block circuits employed in connection with the invention.

Referring to Figure 6 of the drawings, 10 designates a plurality of track blocks, the rails of which are insulated at 11 from each other and which are adapted to be normally connected by jumper circuit 12 having an armature 13 controlled by relay 14. The relay magnet is normally energized through 105 the circuit wires 15 and 16 by the battery 17 and is de-energized only when the

block ahead is occupied by a train which short circuits the circuit wires 15 as clearly illustrated in Figure 6 of the drawing.

By way of practical illustration as shown in Figure 1 of the drawings the rear wheel 20 of the locomotive and the front wheel 21 of the tender are insulated from each other except for their engagement with the rail 22 and the same are included in the circuit 23. The circuit 23 also includes a battery 24, a latch magnet 25, a switch 26 and the cross connection 27 in which is arranged a speedometer controlled circuit closer 28. The latch magnet 25 is arranged in a housing 29 and normally operates when energized by the battery 24 during the closed condition of the circuit 23, to retain the latch 30 in locking position due to the engagement of the arm 31 with the latch arm 32. The speedometer controlled circuit closer 28 included in the cross connection 27 comprises a wiper arm 33 which operates over a contact plate 34 here illustrated of a sufficient length whereby the arm 33 will contact therewith up to the time that the train does not exceed five miles an hour and the purpose of this circuit closer will be hereinafter explained.

Referring to Figure 2 of the drawings, 36 designates one terminal of the brake pipe line which is normally closed by a valve 37 having a valve stem 38 extending outwardly from the valve casing 39. The means which is adapted to co-act with the valve stem 38 to open the valve 37 and bleed the brake pipe line includes a cylinder 40 in which is mounted a sliding piston 41 having a piston rod 42 extending through one extremity of the cylinder in alignment with the valve stem 38 and provided on its free extremity with an abutment head 43. A coiled expansion spring 44 normally forces the piston in a direction to maintain the abutment head 43 out of engagement with the valve stem 38 in which position the piston abuts against and effects the seating of the exhaust valve 44 with its seat to close the exhaust opening 45 in the cylinder head 46. The engagement of the piston with the valve and the valve with its seat serves to space the piston from the cylinder head to leave the inlet 47 open to the space between the piston and the cylinder head. The exhaust opening communicates with a plurality of radial exhaust ports 48 formed in the cylinder head and which communicate to the atmosphere. The valve stem 49 of the exhaust valve 44 is secured to a plunger 50 which operates in an air chamber 51 secured to the cylinder head. The chamber 51 communicates with the cylinder 40 through a pipe 52, the opposite extremities of which are open respectively to the chamber 51 and the cylinder 40 a predetermined distance from the cylinder head designated at 53. A valve cock 54 controls

the communication between the cylinder 40 and the chamber 51 for a purpose to be hereinafter set forth.

The mechanism for admitting air to the cylinder 40 through the intake 47, to operate the piston 41 is controlled by the latch 30 and the same includes an actuator 60 which is provided with a spring pressed bolt 61 normally engaged by the nose of the latch when the magnet 25 is energized. The actuator 60 is secured to the free end of a plunger rod 62 the opposite extremity of which is formed with a head 63 mounted for sliding movement in the cylindrical frame 64, the upper portion of said frame having an adjustable sleeve 65 through which the plunger rod 62 is adapted to slide. A coiled expansion spring 66 normally exerts a tension between the sleeve 65 and the plunger head 63 whereby upon release of the nose of the latch from the bolt 61 the actuator 60 will be moved in a direction to engage the stem 67 of a valve 68. The valve 68 controls communication between a supply pipe 69 leading from the main reservoir and a pipe 70 leading therefrom to the inlet 47 of the cylinder 40. The actuator head is guided through the engagement of the guide rods 71 in the guides 72 to prevent radial turning movement in order to insure at all times the proper alignment of the bolt 61 with the nose of the latch 30. The actuator head is provided with a lug 73 which engages the valve stem 74 of a by-pass valve 75 to effect the unseating of the valve when the actuator is in normal locked position through the engagement of the bolt 61 with the latch 30. The by-pass valve 75 controls communication between the pipe 76 and the by-pass pipe 77, the opposite extremity of said latter pipe communicating with the pipe 70. The opposite extremity of the pipe 76 communicates with a three-way valve 78, the remaining ports of which communicate with an exhaust or drain nipple 79 and a branch pipe 80 leading to the main reservoir. The pipe 70 has interposed therein a needle valve 82 for regulating the flow of air therefrom to the inlet of the cylinder 40 and is further provided with a four-way connection 83 between the point of entry of the by-pass pipe 77 and the needle valve. A discharge pipe 84 establishes communication between the four-way connection 83 and the section of the pipe 70 which lies between the needle valve and the inlet 47. A quick exhaust valve 85 is disposed in the discharge pipe 84 and is normally seated by the pressure of the air entering the pipe 70 but is adapted to unseat automatically upon a back pressure from the cylinder 40. The remaining port of the connection 83 communicates with the throttle control cylinder 86 through the conduit pipe 87. A piston 88 suitably connected with the throttle lever 89 operates in the cylinder 130

86 to close the throttle upon the entrance of the air pressure thereto through the pipe 87.

In use and operation of the system, when the block ahead of the train is clear, the 5 armature 13 of the jumper circuit is closed by the relay magnet 14 which is energized through the wiring 15 and 16 from the battery 17. Should the engineer run past a closed signal due to his failure to observe or 10 for any other reason, the train in the block ahead will have short circuited the wiring 15 and 16 thus deenergizing the relay magnet 14 and opening the jumper circuit 12. As the wheels 20 and 21 of the train straddle 15 the insulated section 11 of the track, the circuit 23 will be broken or ruptured if the train advances at a speed greater than five miles an hour for the reason that the wiper arm 33 will be out of contact with the plate 20 34. Immediately upon the breaking of the circuit 23, the magnet 25 will be deenergized and the arm 31 thrown to a position to permit the latch arm 32 to be released. The nose of the latch 30 will then be free to 25 swing under the tension of the spring 66 thereby permitting said spring to move the actuator head 60 which due to its engagement with the valve stem 67 will unseat the main valve 68. This will result in the feeding 30 of the air from the main reservoir through the pipe 69 to the pipe 70, a part of the pressure traveling through the pipe 87 to the throttle control cylinder 86 to actuate the throttle lever 89 and effecting a closing 35 of the throttle. The remainder of the air will feed through the needle valve 82 into the inlet 47 of the cylinder 40 between the piston 41 and the cylinder head 46. The piston will be moved against the tension of 40 the spring 44^a until the abutment head 43 engages with the valve stem 38, resulting in the unseating of the valve 37 and the bleeding 45 of the brake pipe line. This will effect the application of the brakes to bring the train to a stop. The pressure in the cylinder 40 will be sufficient to maintain the exhaust valve 44 in seated condition and it is assumed that the valve cock 54 is closed for an emergency stop. If a service stop is desired, the valve cock 54 will be open and when the piston 41 uncovers the port 53, a portion of the air will flow through the pipe 52 to the chamber 51 equalizing the pressure on both sides of the plunger 50 and 55 permitting the weight of the same to unseat the valve 44 and exhaust the pressure in the cylinder 40 through the port 45 and the ports 48 to the atmosphere. When the pressure is sufficiently reduced the spring 60 44^a will function to disengage the abutment head 43 of the valve stem 38 thereby releasing the brakes intermittently to obtain the service stop.

After the train has been brought to a stop 65 by this system and the block ahead is clear,

means is provided for resetting the system which includes a reset cylinder 90 having a cylinder head 91 provided with an inlet port 92 from which extends a conduit pipe 93 communicating with the pipe 76 at 70 a point between the three-way valve 78 and the by-pass valve 75. The reset cylinder 90 is carried by the cylindrical frame 64 in alignment therewith and the piston 94 operating therein is provided with a piston rod 75 95 extending through the closed end of the cylinder into the operating frame. The piston 94 is normally advanced toward the cylinder head by means of a coiled expansion spring 96. To reset the system, the three-way valve 78 is manipulated to establish communication between the branch pipe 80 and the pipe 76, thereby opening the pressure from the main reservoir through the pipe 93 to the reset cylinder 90 between the piston 94 and the piston head 91. The piston 94 under this pressure will be moved away from the cylinder head 91 and the stem 95 thereof will engage the plunger head 63, returning the actuator head 60 to 90 its normal position where its bolt 61 will be again engaged by the nose of the latch 30. This will permit the spring pressed main valve 68 to reseat through the disengagement of the actuator head with the valve 95 stem 67, thereby cutting off communication of the main reservoir pressure with the feed pipe 70 to the cylinder 40. At the same time the lug 73 will engage the valve stem 74 of the by-pass valve 75 lifting the same from 100 its seat, the air pressure from the main reservoir will then pass through the pipes 76 and 77 by way of the by-pass valve 75 to the feed pipe 70 retaining the pressure in the cylinder 40 and the brakes in set condition until the three-way valve is again manipulated to cut off communication to the pipe 76 from the main reservoir pressure. This operation of the three-way valve then communicates the pipe 76 with the exhaust or drain nipple 79, permitting the air in the cylinder 40 to return through the exhaust pipe and quick release valve 85, pipe 77, by-pass valve 75, and pipe 76 to disengage the abutment head 43 from the brake 110 105 pipe valve 37. This position of the three-way valve also functions to relieve the reset cylinder 90 of its pressure and at the same time drain the pipe 70 of any air pressure 115 which might accidentally leak through the main valve 68.

Should the engineer attempt to pass a closed signal at a higher rate of speed than permitted by the speedometer controlled circuit closer 28, by manipulating the three-way valve to open the main reservoir pressure into the reset cylinder for the purpose of holding the actuator head against its proper functioning upon breaking of the circuit, the air pressure will at the same 130

time pass from the pipe 76 through the by-pass pipe 77 around the main valve 68 into the pipe 70, thereby operating the piston 41 in the same manner as if the main valve 68 were open. This arrangement defeats any attempt of the engineer to render the device inoperative temporarily and renders the apparatus fool-proof. The apparatus is so constructed that it will perform its intended function regardless of whether an essential part is removed or whether the circuit is broken or shorted.

It is to be understood that the right is reserved to various embodiments other than those actually disclosed herein, to the fullest extent indicated by the broadest meaning of the terms in which the claims are expressed and by modifications in the phraseology of the same.

Having thus described our invention, we claim as new and desire to secure by Letters Patent:

1. In an automatic train control system the combination with an air-brake system including a main reservoir, a brake pipe, and a normally closed exhaust valve in the brake pipe, of means for opening said valve comprising a cylinder, a piston arranged therein and adapted to co-act with said valve upon movement of the piston, a feed pipe communicating respectively with the cylinder and the main reservoir, a feed valve in said feed pipe, an actuator for said feed valve, retaining means for holding said actuator in an inactive position, an electric circuit for controlling said retaining means, a track having insulated blocks, means for breaking and establishing electrical communication between the blocks respectively by the presence or absence of a train in advance, said blocks when in communication serving to complete the control circuit and when out of communication to break said circuit.

2. In an automatic train control system, the combination with an air brake system including a main reservoir, a brake pipe, and a normally closed exhaust valve in the brake pipe, of means for opening said exhaust valve comprising a cylinder, a feed pipe communicating respectively with the cylinder and the main reservoir, a feed valve in said feed pipe, an actuator for said feed valve, a by-pass pipe communicating at one end with the feed pipe between the feed valve and the cylinder and open at its opposite end to the atmosphere, a by-pass valve in said by-pass pipe, said by-pass valve being operable by the actuator when in inactive position, to retain the said by-pass valve open, retaining means for said actuator for normally locking the same in inactive position, an electric circuit for retaining said controlling means, a track having insulated blocks, means for breaking and establishing

electrical communication between the blocks, respectively by the presence or absence of a train in advance, said blocks when in communication serving to complete the control circuit and when out of communication to break the same.

3. In an automatic train control system, the combination with the air brake system thereof including a main reservoir, a brake pipe and a normally closed exhaust valve in said brake pipe, of means for opening said exhaust valve to effect the application of the brakes, comprising a cylinder having a piston arranged therein adapted to co-act with said exhaust valve upon movement of the piston, a feed pipe communicating respectively with the cylinder and said main reservoir, a normally closed feed valve in said feed pipe, an actuator for opening said feed valve, retaining means for holding said actuator in inactive position, means operable by said actuator when in inactive position for opening the feed pipe between the feed valve and said cylinder, an electric circuit for retaining said controlling means, a track having insulated blocks, means for breaking and establishing electrical communication between the blocks, respectively by the presence of absence of a train in advance, said blocks when in communication serving to complete the control circuit and when out of communication to break the same.

4. In an automatic train control system including in combination a track having insulated blocks, means for breaking or establishing electrical communication between said blocks by the presence or absence of a train in advance, of mechanism on each train for throwing off the driving power of the same and simultaneously effecting the application of the brakes when the electrical communication between the blocks is broken comprising an air chamber communicating with the main reservoir of the air brake system, having a piston therein adapted to bleed the brake pipe, a valve for controlling the supply from the main reservoir to the air chamber, an actuator for operating said valve, means for retaining said actuator in a position to effect the closing of said valve, pneumatic means for moving said actuator to an inactive position, said pneumatic means having communication with the main reservoir, a valve for controlling communication between the reservoir and said pneumatic means, means operable by the actuator when in an inactive position for draining the connection between the feed valve and the air chamber, a control circuit for said actuator, retaining means normally closed when electrical communication between the blocks of the track is established.

5. In an automatic train control system including in combination a track having insulated blocks, means for breaking or es-

- tablishing electrical communication between said blocks by the presence or absence of a train in advance, of mechanism on each train for throwing off the driving power of 5 the same and simultaneously effecting the application of the brakes when the electrical communication between the blocks is broken comprising an air chamber communicating with the main reservoir of the air 10 brake system, having a piston therein adapted to bleed the brake pipe, a valve for controlling the supply from the main reservoir to the air chamber, an actuator for operating said valve, means for retaining said 15 actuator in a position to effect the closing of said valve, pneumatic means for moving said actuator to an inactive position, said pneumatic means having communication with the main reservoir, a valve for controlling communication between the reservoir and said pneumatic means, means operable by the actuator when in an inactive position for draining the connection between the feed valve and the air chamber, 20 a control circuit for said actuator retaining means normally closed when electrical communication between the blocks of the track is established, and pneumatic means operable when the feed valve is open for effecting 25 the movement of the throttle to throw off the power.
6. In an automatic train control system, the combination with an air-brake system including a main reservoir, a brake pipe, 30 and a normally closed exhaust valve in the brake pipe, of means for opening said valve comprising a cylinder, a piston arranged therein and adapted to coact with said valve upon movement of the piston, a feed pipe 35 communicating respectively with the cylinder and the main reservoir, a feed valve in said feed pipe, an actuator for said feed valve, retaining means for holding said actuator in an inactive position, an electric 40 circuit for controlling said retaining means, a track having insulated blocks, means for breaking and establishing electrical communication between the blocks respectively by the presence or absence of a train in advance, said blocks when in communication 45
- serving to complete the control circuit and when out of communication to break said circuit, and means associated with the cylinder for intermittently causing the piston to coact with the exhaust valve whereby intermittent application of the brakes is obtained. 55
7. In an automatic train control system, the combination with an air-brake system including a main reservoir, a brake pipe, and a normally closed exhaust valve in the brake pipe, of means for opening said valve comprising a cylinder, a piston arranged therein and adapted to coact with said valve upon movement of the piston, a feed pipe 60 communicating respectively with the cylinder and the main reservoir, a feed valve in said feed pipe, an actuator for said feed valve, retaining means for holding said actuator in an inactive position, an electric 65 circuit for controlling said retaining means, a track having insulated blocks, means for breaking and establishing electrical communication between the blocks respectively by the presence or absence of a train in advance, said blocks when in communication 70 serving to complete the control circuit and when out of communication to break said circuit, and means associated with the cylinder for intermittently causing the piston to coact with the exhaust valve whereby intermittent application of the brakes is obtained. 75
6. In an automatic train control system, the combination with an air-brake system including a main reservoir, a brake pipe, and a normally closed exhaust valve in the brake pipe, of means for opening said valve comprising a cylinder, a piston arranged therein and adapted to coact with said valve upon movement of the piston, a feed pipe 80 communicating respectively with the cylinder and the main reservoir, a feed valve in said feed pipe, an actuator for said feed valve, retaining means for holding said actuator in an inactive position, an electric 85 circuit for controlling said retaining means, a track having insulated blocks, means for breaking and establishing electrical communication between the blocks respectively by the presence or absence of a train in advance, said blocks when in communication 90 serving to complete the control circuit and when out of communication to break said circuit, and means associated with the cylinder for intermittently causing the piston to coact with the exhaust valve whereby intermittent application of the brakes is obtained, said means comprising an air receiving chamber having communication with the cylinder a predetermined distance from the air inlet of the feed pipe, a plunger mounted in the chamber, a check valve control exhaust in the cylinder normally closed by the internal pressure, means for cutting off or establishing communication between the cylinder and said chamber, said plunger adapted to coact with the check valve upon movement of the piston to uncover the communication between the cylinder and the chamber. 95
